CONDUIT CAP

Ralph G. Whitlock, Los Angeles, and Lewis Sharp, Huntington Park, Calif., assignors to Federal Foundation, Inc., Las Vegas, Nev., a corporation of Nevada

Application April 9, 1934, Serial No. 719,698

9 Claims. (Cl. 221—67)

This invention relates to liquid storage and dispensing systems such as used in gasoline service stations, and has for its particular purpose the prevention of illicit dumping of gasoline in the tanks of the service stations.

The high Government taxes on gasoline sold for use in motor cars has resulted in an illicit or bootleg business in gasoline of tremendous proportions. It is to the interest of the Government, as well as the oil companies, to curb this bootlegging business to as great an extent as possible.

It is an object of this invention to provide a conduit cap for use on the fill pipe of gasoline service station storage tanks which will provide such a check upon the filling of these storage tanks that it will be impossible for these tanks to be fraudulently filled with gasoline without this becoming known to the Government officers or to the inspectors of the major oil company whose brand of gasoline is supposed to be contained in said tank.

Other objects and advantages will be made manifest in the following description taken in connection with the accompanying drawings, in which:

Fig. 1 is a diagrammatic side elevational view of a preferred embodiment of the conduit cap of this invention installed in connection with the fill pipe and dispensing pipe of a gasoline filling station storage tank.

Fig. 2 is an enlarged plan view of the conduit cap shown in Fig. 1 with the outer cover of the cap open.

Fig. 3 is a view similar to Fig. 2 and showing the inspected lock cover removed, the token well cover swung open, and the side closure member swung to open position.

Fig. 4 is a fragmentary diagrammatic vertical sectional view of the dispensing pipe shut-off valve and operating mechanism of this invention.

Fig. 5 is a diagrammatic fragmentary vertical sectional view of a sounding rod used in connection with this invention.

Fig. 6 is a transverse sectional view taken on the line 6—6 of Fig. 5.

Fig. 7 is a transverse sectional view taken on the line 7—7 of Fig. 2.

Fig. 8 is a horizontal sectional view taken on the line 8—8 of Fig. 7 and looking upward.

Fig. 9 is a horizontal sectional view taken on the line 9—9 of Fig. 7 and looking downward.

Fig. 10 is a view similar to Fig. 9 showing the operating parts in different operating positions.

Fig. 11 is a diagrammatic fragmentary vertical

sectional view through the token well of this invention and illustrating the token magazine disc when locked against rotation by a token disposed in the bottom of the token well.

Fig. 12 is a view similar to Fig. 11 illustrating the manner of removing the token from the well.

Fig. 13 is a view similar to Fig. 11 illustrating the manner in which the token magazine disc of this invention is locked against further rotation when the tokens have been exhausted from the magazine.

Fig. 14 is a view similar to Fig. 13 showing the released position of the lock shown in Fig. 13.

Fig. 15 is a fragmentary vertical sectional view illustrating the ratchet springs and cooperating ratchet pins on the magazine disc of this invention.

Fig. 16 is an enlarged fragmentary horizontal sectional view taken on the line 46—46 of Fig. 7 and illustrating the ratchet means for controlling the opening and closing of the fill pipe opening closure member.

Fig. 17 is a view similar to Fig. 16 further illustrating said closure means.

Fig. 18 is a diagrammatic view showing a novel form of gauge for use on a gasoline storage tank.

Fig. 19 is an enlarged vertical sectional view taken on line 19—19 of Fig. 18.

Referring specifically to the drawings, and particularly Fig. 1, it will be noted that the conduit cap 20 of the invention is mounted on the upper end of a fill pipe 21 having an elbow 22 connecting with a T fitting 23 from which a lower fill pipe 24 extends downwardly to an underground gasoline storage tank (not shown). Fitted into the upper end of the T fitting 23 is a nipple 25 and cap 26, respectively, the latter having a small diameter sounding rod guide pipe 27 provided with a cap 28 and disposed in alignment with the lower fill pipe 24. Also extending up from the aforementioned storage tank is a dispensing pipe 30 which connects with one end of a valve 31 which in turn connects to a pipe 32, the latter leading to a suitable gasoline dispensing service pump. Extending between the valve 31 and the conduit cap 20 is a valve stem housing pipe 33. The conduit cap 20 and directly associated parts are contained in a concrete manhole 35 having a manhole cover 36.

The conduit cap 20 of this invention includes a housing 40 having a floor 41 and a continuous side wall 42, this housing having a plan as shown in Figs. 2, 3, 8, 9, and 10. It is thus seen that this housing is substantially circular in shape excepting for a closure member shaft mounting

bay 43 extending laterally therefrom. Hingedly mounted on suitable lugs on the wall 42 is an outer cover 44 as shown in Figs. 2, 3, and 7. Formed in the circular part of the housing side wall 42 near its upper edge is a recess 46, the purpose of which will be made manifest hereinafter. Secured as by cap screws 47 to the floor 41 of the housing 40 is a threaded flange 48 into which the fill pipe 21 is screwed to mount the conduit cap 20 on this pipe.

Provided in the upper surface of the floor 41 is a fill pipe opening closure valve seat 50 in which is disposed a flat valve member 51 having a short stem 52 provided thereon. Covering the valve seat 50 and secured to the housing floor 41 as by cap screws 53 is a circular flange 54 of a fill pipe vestibule sleeve 55 having a fill pipe opening 56 disposed in vertical alignment with the fill pipe 21. The flange 54 has a suitable bearing opening through which the stem 52 extends upwardly, there being a suitable packing gland formed in this sleeve about the stem 52 to prevent leakage of gasoline around this stem. Secured on the upper end of the stem 52 is an arm 57 for operating the valve member 51. The sleeve 55 has an upper portion 60 of smaller diameter than the lower portion so as to form a shoulder 61 near the base of this sleeve, the upper portion 60 of the sleeve being threaded both internally and externally as clearly shown in Fig. 7. These internal threads are adapted to receive a plug 63 to form an air-tight seal in the upper end of the sleeve 55. Rotatably resting on the shoulder 61 is a token depositary floor disc 65 having a lug 66 extending upwardly therefrom near its outer edge and by which this disc is adapted to be rotated. Supported on the wall 42 and extending across the mouth of the bay 43 opposite the edge of the token depositary disc 65 is a token retaining wall 67.

Secured by a pin 70 and screws 71 to the wall 42 in the bay 43 of the housing 40 is a bearing block 72 in which is journaled a spindle 73, on the upper end of which is rigidly mounted a fill pipe opening closure member 74, the spindle 73 having a shoulder 75 at the upper end of a reduced portion 76, there being a ratchet wheel 77 and a magazine disc actuating arm 78 keyed onto the reduced diameter portion 76 of the spindle 73. The lower end of the portion 76 of the spindle is threaded and a nut 79 disposed thereon holds the ratchet gear 77 and arm 78 upwardly against the shoulder 75. The lower end 80 of the spindle 73 is of still further reduced diameter, has a notch 81 therein, and extends downwardly through a suitable opening in the housing floor 41 into the upper end of the valve rod housing 33. As shown in Figs. 4 and 7, the notch 81 receives a pin 83 provided in the upper end of a hollow valve rod 84 which extends downwardly through the housing 33 and connects with the stem 85 of the dispensing pipe shut-off valve 31, this valve having a butterfly disc 86 secured upon the stem 85.

Trapped between the lower face of the bearing block 72 and the gear 77 is a ratchet control disc 90 having small notches 91 and 92, and a large notch 93 formed in the periphery thereof. Provided on the ratchet gear 77 and extending upwardly therefrom is a pin 94 which is disposed in the large notch 93. The bearing block 72 has a floor portion 96, on the lower surface of which is attached a bracket 97 providing two arms which extend downwardly and support at their lower ends a pair of ratchet spring dogs 101 and 102. The spring dogs 101 and 102 are under ten-

sion and urged inwardly towards the ratchet gear 77. An upper portion of each of these spring dogs 101 and 102, however, lies opposite the ratchet control disc 90 and the small notches 91 and 92 are so spaced that when the gear 77 is rotated in one direction the pin 94 engages the disc 90 so as to rotate the notch 91 out of registry with the dog 101 as shown in Fig. 16, and permits the dog 102 to enter the notch 92 into ratcheting relation with the teeth of the gear 77. When the gear 77 is rotated in the opposite direction a sufficient distance the pin 94 engages the disc 90 at the other end of the notch 93 so as to shift the dog 101 into ratcheting relation with gear 77 and remove dog 102 therefrom. Thus, one of the dogs 101 and 102 is always engaged with the teeth of the gear 77.

The arm 57 of the valve member 51 is connected to the arm 78 by a link 110 (see Fig. 7) by which swinging of the arm 78 operates the valve member 51. Extending upwardly from the arm 78 is a boss 114 having a ratchet pawl 115, this pawl being continuously urged by a spring 116 so as to swing this pawl in an anti-clockwise direction when viewed as shown in Figs. 9 and 10. The pawl 115 has a lug formed thereon for a purpose which will be made manifest hereinafter.

All of the parts hitherto described in the mechanism of the conduit cap 20 remain permanently installed on the fill pipe 21 throughout the use of this device. There is a removable token magazine, locking and counting mechanism assembly 120, however, which is inserted in and removed from the conduit cap 20 incidental to the continued functioning of the conduit cap 20 in regular commercial use. In order for the assembly 120 to be inserted into the device the outer cover 44 must be open and the fill pipe opening closure member 24 swung into full open position as shown in Fig. 3, whereupon the assembly 120 may be inserted in or removed from place in the conduit cap 20. With this explanation in mind, it will be noted that the removable assembly 120 includes a body having an upper floor 121 and a sleeve 122 extending downwardly therefrom, the sleeve 122 freely receiving the sleeve 55 and the outer edge of the floor 121 being circular and received in the recess 46 in the upper edge of the housing side wall 42 and a corresponding recess provided in the bearing box floor 96. Secured to the floor 121 and extending into a complementary recess in the floor 96 is a pin 123 for indexing the assembly 120 in its proper position in the conduit cap. When the assembly 120 is in place a ring nut 124 holds the assembly 120 firmly in place in the cap.

Referring now to Figs. 3, 7, and 8, it will be noted that a combination inspection lock 130 is mounted on the floor 121, the operating knob 131 of this lock extending upwardly through the floor 121 as shown in Fig. 3. This knob is normally covered by a small cap 133, as shown in Fig. 2, which can readily be taken off by removal of two screws 134. The lock 130 is connected by linkage 135 to an inspection counter 136, this counter being viewable through a hole 137 in the floor 121. Also provided on the under surface of the floor 121 is a dump counter 138, the total of which may be viewed through a hole 139 as shown in Fig. 2. Provided on the floor 121 and extending downwardly therefrom is a stud 140, at the lower end of which are provided two pairs of spring ratchet dogs 141 and 142, the action of which will be made manifest hereinafter. Formed in the floor 121 is a token well tube 147, this extend-

ing downwardly with a formation on its lower end which will be described hereinafter. Pivoted on the well tube 147 as shown in Figs. 8 and 11 is an empty magazine locking dog 144, the latter being 5 operatively connected to the inspection lock 130 by a link 145. Mounted on a spindle 150 in the floor 121 is a swinging door 151 which is spring urged into a position covering the well tube 147.

The sleeve 122 is reduced in diameter at its lower 10 end to form shoulders 160 and 161, the lower end of the sleeve 122 then being threaded to receive a nut 162. Firmly held between the nut 162 and the shoulder 161 is a check token retaining disc 163 having a single opening 164 in the periphery thereof, the purpose of which will be made manifest hereinafter. Rotatably mounted on the sleeve 122 between the disc 163 and the shoulder 160 is a token magazine disc 168. This disc has a series of pockets 170 formed in its upper surface 20 near the outer edge of the disc, as clearly shown in Figs. 9 and 10 and an identical series of pockets 171 formed in the lower surface of the disc 168, the pockets 171 being in vertical alignment with the pockets 170. The pockets 170 and 171 are for 25 the purpose of retaining tokens 172 and 173, respectively, therein, the tokens 172 being transaction tokens and the tokens 173 being deposited or check tokens. Extending upwardly from the upper surface of the disc 168 is a series of uniformly spaced pins or pegs 176, one for each of the pockets 30 170. Extending downwardly from the disc 168, as shown in Fig. 7, and right at the periphery of this disc is a series of pins 178, these pins being in alignment with the pin 66 on the token de- 35 pository floor 65, so that no matter how the assembly 120 is placed in the device one of the pins 176 will be close to and in rotational alignment with the pin 66.

The perimeter of the magazine disc 168 is pro- 40 vided with uniformly spaced ratchet teeth 180, one of which is provided for each of the token pockets 170, these teeth being adapted to be engaged by the pawl 115 as shown in Figs. 9 and 10.

45 Operation

To begin with, it is noted that the conduit cap of our invention is especially adapted for use on the fill pipe of storage tanks for gasoline filling 50 stations where these stations have contracts with oil companies for dispensing only certain brands of gasoline from that tank and/or where gasoline is taxed by a governmental agency and the Government desires to check up on all the gasoline dumped into that tank. It thus becomes para- 55 mount that a system be devised for governing access to that fill pipe so that if gasoline is dumped into that pipe without an accounting being made of it this fact will be discovered.

The system for which we have devised our invention contemplates that an inspector representing the oil company or the Government will charge each conduit cap with a certain number of transaction tokens which are placed in the pockets 60 170. The pockets 171 are at the same time charged with depositary or check tokens. The check tokens may be duplicates of the transaction tokens respectively in the pockets 170 immediately above said check tokens.

This system also contemplates that the driver 70 of the dump wagon representing the oil company has access to the device by carrying a key to a padlock (not shown) of the outer cover, or by having knowledge of the combination of the outer cover lock, if a combination padlock is used. When

making each dump into the tank through the fill pipe 21 the conduit cap 20 is operated to give access to this fill pipe and the truck driver in so doing receives a transaction token, operates the dump counter 138 and deposits a check token in the conduit cap 20 as the record of his opening the conduit cap and having access to the fill pipe 21. At the end of each day the dump truck operator is required to turn in at his headquarters all of the transaction tokens received from conduit caps 10 in making his daily rounds and make a complete record of the places at which he has dumped gasoline. Following up the truck operators are inspectors who check up on the records turned in by the dump truck drivers by opening up the conduit caps and inspecting the record left in the cap in the form of deposited check tokens.

In the above briefly outlined system the conduit cap operates as follows: In the first place, the inspector has the cap in the condition shown 20 in Fig. 3, whereupon he unlocks the inspector's combination lock 130, removes the ring nut 124 from the upper end of the sleeve 60, and seizing the knobs 131 and 152 lifts the assembly 120 from the conduit cap. Now, by inverting the assembly 25 120 he may insert check tokens through the opening 164 in the check token retaining disc 163 into the check token pockets 171 and by rotating the token magazine disc 168 can fill all of the pockets 171 with check tokens. Then the inspector rein- 30 35verts the assembly 120 into upright position and without rotating the disc 168 reaches in between the floor 121 and the disc 168 and fills all of the pockets 170 with transaction tokens. It is to be understood, of course, that the pockets 170 and 171 40 are directly opposite each other and the tokens placed in these respective pairs of pockets may preferably have special indicia distinguishing each pair from the others, so that for each transaction token placed in the pockets 170 there is only 45 one of the check tokens corresponding thereto and that check token is placed in the pocket 171 directly therebeneath. It is to be noted that while the closure member 74 is swung open as shown in Figs. 3 and 10 the lug 118 on the ratchet pawl 115 is against the wall 42 of the housing 40 so as to prevent the pawl 115 swinging outwardly when the token magazine disc 168 is not opposite this pawl as when the assembly 120 is removed 50 from the conduit cap 20.

With the magazine disc 168 thus completely charged with transaction and check tokens, the assembly 120 is now slipped back into place in the conduit cap 20, the ring nut 124 is screwed back into place, the inspector's combination lock 130 55 is locked, the cap 133 is secured in place over this lock by the screws 134, the inspector takes note of the numbers displayed by the counters 136 and 138 through the openings 137 and 139, swings the closure member 74 into its closed position as 60 shown in Fig. 2, shuts the outer door 44, and locks it with its padlock (not shown).

Now the driver comes along to make a dump of gasoline in this particular storage tank. He is equipped with a key to the padlock (not shown) 65 on the outer cover 44 and opens this padlock and swings open the outer cover. He then swings the closure member 74 in a clockwise direction about half way towards the full open position in which it is shown in Fig. 3. At this point it is desired to 70 point out in Figs. 11, 12, and 13 that the pockets 170 are shallower than the transaction tokens 172 resting in these pockets, that the left-hand side of the well tube 147 is of sufficient height to permit the tokens in the pockets 170 to pass under 75

- this wall in entering the well tube 147, and that the right-hand side of the tubular token well tube 147 extends downwardly close to the upper surface of the magazine disc 168, so as to prevent 5 a token in a pocket 170 from travelling to the rightward out of the well tube 147. It is also to be noted that the empty magazine locking dog 144 is normally resting on top of the transaction tokens as shown in Fig. 11. When the truck driver starts 10 to open the closure member 74 as just mentioned, the pawl 115 engages the next adjacent tooth 180 as shown in Fig. 9 and rotates the disc 168 to shift a transaction token into engagement with the right wall of the well tube 147 and this prevents further rotation of the disc 168 and also prevents further swinging of the closure member 74. It thus becomes necessary for the truck driver to insert a tool 200, as shown in Fig. 12, into a hole provided in the middle of the transaction token 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 conduit cap 20 is used in this manner the closure member 74 is freely swingable from the position in which it is shown in Fig. 2 to the position in which it is shown in Fig. 3 and is then free to be 5 returned to the position in which it is shown in Fig. 2. When thus opened and closed the closure member 74 operates the dump counter 138 so that this counter at all times accurately registers the number of times which the closure 10 member 74 is opened and closed. It is, of course, clear that this freedom of movement of the closure member 74 results from the fact that when the device is used without tokens the absence of tokens in the pockets 170 prevents the locking of 15 the closure member 74 in partially opened position as this normally occurs as shown in Fig. 11 when this device is being used with tokens.

It is also believed clear that the outer cover 44 of the invention is not an indispensable element 20 in the combination and is mainly provided for to keep dust out of the device as well as indicating when it is open that a dumping transaction is in progress. Under some circumstances it is desirable to eliminate the outer cover 44.

25 While we have shown the closure member 74 as actuating the shut-off valve 31 when the closure member 74 is opened, it is to be understood it is not always essential that the closure member be connected with the shut-off valve 31 and that in 30 some situations may be preferable where it is desired to avoid interrupting the dispensing of gasoline from the pumps in a service station to allow the shut-off valve 31 to remain open during the dumping of gasoline through the conduit 35 cap 20.

The use of the conduit cap 20 without tokens is for the purpose of expediting the opening and closing of the closure member 74 and where such a close check as provided by the tokens is unnecessary. It will be noted that even where the tokens are eliminated the closure member 74 is still provided with the ratchet means 77-90-40 101-102 and the dump counter 136, actuation of which by the closure member 74 is assured by this 45 ratchet means. Accordingly, the counter 138 accurately registers the number of times the closure member 74 is completely opened and closed, and as this occurs only once for each dump of gasoline made in the storage tank equipped 50 with the conduit cap 20 an accurate record of the number of dumps made in this tank is shown by the counter 138.

What we claim is:

1. The combination of: a fill pipe; a head on 55 said pipe; a pipe closure member movably mounted on said head and having a position closing said pipe and a position freeing said pipe to permit access thereto; means provided on said head for discharging a token into a position where it may be taken by the operator for 60 each cycle of actuation of said member to permit access to said fill pipe; and means for coacting with a token before its removal to prevent further actuation of said closure member until said 65 token has been taken up by said operator.

2. A combination as in claim 1 in which said pipe closure member is disposed away from its normal fill pipe closing position when movement of said closure member is prevented by said 70 token.

3. A combination as in claim 1 in which said pipe closure member is disposed away from its normal fill pipe closing position when movement of said closure member is prevented by said 75 token; and a cover for said head which snugly

fits over said closure member when said closure member is in fill pipe closing position, and embodying means for coacting with the closure member whereby the cover is prevented from being returned to its normal head covering position when said closure member is disposed away from its normal fill pipe closing position. 5

4. The combination of: a fill pipe; a head on 10 said pipe providing a depository chamber; a pipe closure member movably mounted on said head and having a position closing said pipe and a position freeing said pipe to permit access thereto; means provided on said head for delivering a token into a position where it may be taken up by the operator, one of said tokens 15 being delivered for each cycle of actuation of said member to permit access to said fill pipe; and means for concurrently depositing a check token in said depository chamber for each delivery of a token as aforesaid. 20

5. In a conduit cap the combination of: a head having a fill pipe opening; a fill pipe closure member movably mounted on said head and having a position closing said opening and a position freeing said opening to permit access 25 thereto; and means provided on said head for depositing check tokens contained therein one for each cycle of operation of said closure member.

6. In a conduit cap the combination of: a 30 head having a fill pipe opening; a fill pipe closure member movably mounted on said head and having a position closing said opening and a position freeing said opening to permit access thereto; means preventing reversal of direction 35 of movement of said closure member either during an opening movement or a closing movement thereof; means provided on said head for delivering a token into a position to be taken up by the operator for each cycle of actuation of 40 said closure member; and means for coacting with a token before its removal for halting said closure member in the midst of a cycle of operation until said token shall have been taken up by the operator. 45

7. In a liquid storage and dispensing system, the combination of: a tank having receiving and dispensing openings; a closure for said receiving opening; shut-off means for said dispensing opening; a token magazine; means connected 50 with said closure member to shut off said shut-off means when said closure member is moved away from said receiving opening; means for delivering a token from said magazine into position where this can be taken up by the operator 55 during each opening and closing cycle of said closure member; and means preventing reversal of direction of movement of said closure member either during an opening movement or a closing movement thereof. 60

8. In a conduit cap the combination of: a head having a fill pipe opening; a fill pipe closure member movably mounted on said head and having a position closing said opening and a position freeing said opening to permit access 65 thereto; means preventing reversal of direction of movement of said closure member either during an opening movement or a closing movement thereof; means provided on said head for delivering a token into a position to be taken up 70 by the operator, said token being so delivered in the midst of a cycle of actuation of said closure member; and means for coacting with said token before its removal for halting said closure member when said token is so delivered until said 75

token shall have been taken up by the operator.

9. In a conduit cap the combination of: a head having a fill pipe opening; a fill pipe closure member movably mounted on said head and having a position closing said opening and a position freeing said opening to permit access thereto; means preventing reversal of direction of movement of said closure member either during an opening movement or a closing movement thereof; means provided on said head for de-

livering a token into a position to be taken up by the operator, said token being delivered during an opening movement of said closure member; and means for coacting with said token before its removal for preventing completion of the opening of said closure member until said token shall have been taken up by the operator. 5
